UNITED STATES PATENT OFFICE

ERNEST L. NORBERG, OF SAN FRANCISCO, CALIFORNIA

LAVATORY

Application filed March 30, 1931. Serial No. 526,160.

My invention relates to toilet apparatus and more particularly it relates to a novel dental lavatory or a wash basin which is adapted to serve as a cover for the flush tank 5 of a toilet bowl.

Heretofore, in equipping bath rooms and the like, it has been customary to supply only one wash basin and the users of the bath room have been compelled to use the same basin 10 for washing purposes that others use for brushing their teeth and for gargling. Such conditions are unsanitary and unless the basin is kept immaculate at all times, there is danger of contracting contagious diseases. 15 In some instances a separate throat and dental lavatory is provided, but the cost of such equipment is prohibitive except in elaborate installations.

It is a general object of my invention to 20 provide a basin which can be disposed over the flush tank of a toilet and which utilizes the overflow pipe of the tank as a drain.

Another object is to provide a basin which 25 is adapted to be supported by the flush tank of a toilet and which has a shape such that the position of the toilet does not interfere with the use of the basin.

Another object is to provide a basin of the 30 character described which serves as a cover for the flush tank.

Still another object is to provide a basin which saves space and which is economical in cost.

These and other objects and advantages are 35 attained in the embodiments of my invention illustrated in the accompanying drawing, in which:

Fig. 1 is an elevational view of an installation embodying the principles of my invention.

Fig. 2 is a side view showing the flush tank and basin of my invention in cross section.

Fig. 3 is a plan view of the embodiment 45 illustrated in Figs. 1 and 2.

Fig. 4 is a plan view of a modification.

In its preferred form my invention comprises a basin which is adapted to be supported by the flush tank of a toilet and which serves as a cover for the flush tank. An 50 outlet is provided for the basin which uti-

lizes the overflow pipe of the flush tank for a drain and if desired, an overflow conduit can be provided for the basin which also communicates directly with the overflow pipe of the flush tank. If desired, the basin can 55 be provided with a protective back which is adapted to be secured to the wall on which the flush tank is mounted by means of a removable spout, which spout also serves to deliver water to the basin. The basin can 60 have a shape such that the forward portion of the basin is offset from the line of the toilet so that the position of the toilet does not interfere in any way with the use of the basin or, if desired, the outline of the 65 basin can have a contour which permits easy access to the basin from either side of the toilet.

While the basin of my invention is particularly suitable for a dental lavatory and 70 thus can serve as an auxiliary fixture in conjunction with the main wash basin of an installation, the invention is not limited to such use. It may be desirable in close quarters, for example, to utilize the basin of 75 my invention as the main basin or as the sole basin of the installation.

Referring now to the drawing, I have shown a toilet bowl 16 adapted to be flushed by water supplied from a flush tank 17. The 80 water in the flush tank 17 is adapted to be replenished by the action of a suitable float valve (not shown) or its equivalent, in accordance with the usual practice for such installations.

An overflow pipe 18 is provided for precluding the water in the tank from exceeding a level which is above the upper or open end of the overflow pipe. A flush 85 valve 19 controls the flow of water from the tank 17 into the toilet bowl 16 and is adapted to be operated by suitable linkage (not shown) actuated by a handle 21 conveniently placed on or near the flush tank. When 90 the water in the tank 17 rises to the top of the overflow pipe 16, due to leakage in the supply valve or from any other cause, any further rise in the level of the water is prevented, since the excess water is carried away 95 100

through the pipe 18 and has clear passage through a fitting 22 into the bowl 16.

Over the top of the flush tank 17 and serving as a cover therefor I provide a basin 23. The basin 23 is preferably provided with a protective and sanitary back 24 and a spout 26 for delivering water to the basin under the control of the faucets 27 and 28 preferably passes through the back 24. The spout 26 is preferably made removable, as by providing a threaded connection 29 between the spout and the delivery pipe extending from the faucets 27 and 28. A suitable rose 31 can be secured to the spout 26 which serves to engage the back 24 and thereby firmly retain the basin 23 on the tank 17 and against the wall 32.

A suitable outlet 33 adapted to be closed by a plug 34 is provided at the bottom of the basin and an overflow conduit 36 can extend between overflow ports 37 in the basin to a point near the outlet 33. The outlet from the basin communicates directly with the overflow pipe 18 and to preclude any of the contents of the basin from discharging into the water 38 in the tank 17, a conduit 39 can be provided from the outlet which extends for a short distance into the mouth of the overflow pipe. Thus, the entire discharge of the basin is delivered directly into the overflow pipe 18 and into the toilet bowl 16 without in any way contaminating the water in the flush tank 17, which for sanitary reasons and to prevent clogging of the system must be kept fairly clean.

The conduit 39 extending into the overflow pipe 18 is preferably of smaller diameter than the mouth of the overflow pipe so that it does not interfere with the normal function of the overflow pipe. If desired, the mouth of the overflow pipe can be flared outwardly, as shown, thereby permitting the use of a discharge conduit 39 of larger diameter.

In the embodiment of the invention illustrated in Figs. 1 to 3, the basin 23 has a semi-circular shape, thereby enabling convenient access to the basin from either side of the toilet and the position of the toilet does not seriously interfere with standing room adjacent the basin.

If desired, the basin can have a semihexagonal or semi-octagonal outline thereby presenting a rectilinear surface toward a person standing on either side of the basin. In the modification illustrated in Fig. 4, for example, I have shown one form of basin having a shape such that it presents a rectilinear surface toward the user. In this modification, however, the front of the toilet bowl 16 is offset from the front of the basin 41. It will be noticed that the edge 42 of the basin makes an acute angle with a vertical plane lying perpendicular to the front of the toilet bowl, indicated by the dot-and-dash line in Fig. 4, and

thus there is no interference with the standing room in front of the basin.

From the foregoing the advantages of my novel basin will be apparent. The basin can be substituted for the basin heretofore commonly employed or it can be used as an auxiliary dental lavatory in conjunction with the main basin of the installation. By employing the overflow pipe of the flush tank as a drain, extra plumbing is avoided and the trap of the toilet bowl serves as a trap for the basin. As hereinbefore explained, the system is clean and sanitary since the drainage from the basin flows directly into the overflow pipe and into the closet bowl and no part of the waste is deposited in the water within the flush tank 17.

While I have shown and described certain preferred embodiments of my invention, I do not wish to be limited thereto, since the invention as defined in the appended claims can be embodied in a plurality of other forms.

I claim:

1. In a flush tank for a toilet bowl, an overflow pipe for precluding the water in the tank from exceeding a predetermined level, a cover for said flush tank, said cover being in the form of a basin, an outlet at the bottom of the basin, said outlet communicating directly with said overflow pipe, and said cover having an outline which presents at least one rectilinear edge making an acute angle with a vertical plane lying perpendicular to the front of the toilet bowl, whereby the toilet bowl does not interfere with the use of the basin.

2. A toilet bowl, a flush tank disposed directly behind said toilet bowl, a cover for said flush tank, and a wash basin in said cover, said wash basin having a front edge which makes an acute angle with the vertical plane passing through the line of centers of said toilet bowl and said flush tank, whereby said toilet bowl presents no interference with the standing room of a user of the basin.

In testimony whereof, I have hereunto set my hand.

ERNEST L. NORBERG.
